TROUSERS OR SIMILAR ARTICLE

William B. Murphy, Crandall, Tex.

Application February 13, 1952, Serial No. 18,503

Term of patent 14 years

(Cl. D3—17)

To all whom it may concern:

Be it known that I, William B. Murphy, a citizen of the United States, residing at Crandall, in the county of Kaufman and State of Texas, have invented a new, original, and ornamental Design for Trousers or Similar Article, of which the following is a specification, reference being had to the accompanying drawing, forming part thereof.

I claim:

The ornamental design for trousers or similar article, substantially as shown and described.

WILLIAM B. MURPHY.
